State of Massachusetts.
County of Suffolk. 4.

I, the thirty-first day of December, A. D. 1832, before the subscriber personally appeared, James Hale, of Boston, in the state of Massachusetts, and made and declared that he is the inventor of an improvement in the binding hay under the Patent Act for which Letter Patent was granted to him on the twenty-sixth day of June, A. D. 1832, and that the annexed drawing is a full and clear description of the invention described in said Letter Patent. R. H. Colby.
Witness of these.
